MACHINE FOR AFFIXING OPENING THREADS TO ENVELOPES

Lester A. Cherry and Clarence N. Fuller, Buffalo,
N. Y., assignors to H. W. Hilliard Co. Inc.,
Buffalo, N. Y., a corporation of New York

Application September 9, 1932, Serial No. 632,382

59 Claims. (Cl. 93—76)

This invention relates to improvements in machines for affixing threads to envelopes in order that they may be quickly and conveniently opened after having been sealed. More particularly the invention is concerned with a machine for applying such threads to completely formed envelopes, the invention contemplating a machine which is adapted to affix an opening thread adjacent the juncture of the sealing flap and the body of the envelope so that when the latter is sealed the thread lies in the fold between the flap and the body of the envelope. The thread extends beyond the envelope body and provides a protruding portion which may be grasped and pulled in a direction transverse of the envelope fold to open the envelope along the fold.

One object of the invention is to provide a machine in which the envelopes are firmly secured to the envelope carrier while the opening threads are being affixed, thereby insuring accurate positioning of the said threads.

A further object is to provide a machine which is capable without the necessity of adjusting the parts thereof of applying threads to envelopes of varying widths.

A still further object is to provide a construction wherein the moving parts are immediately brought to rest in the event that the envelope feed mechanism fails to deposit an envelope upon the envelope carrier at the proper time.

A still further object is a novel construction and arrangement of the various mechanisms utilized in the performance of the several operations whereby the opening threads may be affixed to the envelopes accurately and rapidly.

A still further object is to provide a construction wherein the parts may be removed and replaced with facility.

The invention is illustrated in the accompanying drawings, in which:

Figure 1 is a front elevation of the machine.

Figure 2 is a view in elevation of one side of the machine.

Figure 3 is a rear elevation of the machine.

Figure 4 is a view similar to Figure 2 but of the opposite side of the machine.

- 30 Figure 41 is a fragmentary section of the clutch taken along line 41—41 of Figure 40.
- Figure 42 is a similar section showing the relation of the clutch parts when the clutch is engaged.
- 35 In general the machine includes a rotor which is adapted to provide a plurality of envelope receiving stations. The rotor is caused to rotate so as to move the said stations successively to an envelope receiving position with relation to a magazine in which the envelopes to which opening threads are to be affixed are carried. As
- 40 each station moves to an envelope receiving position an envelope is withdrawn from said magazine and deposited upon the rotor. The operations performed after the envelope is deposited upon the rotor are, in the order of their performance: (1) securing the envelope to the rotor; (2) opening the sealing flap of the envelope and holding it in said position; (3) feeding a section of a continuous thread to which an adhesive is applied adjacent the juncture of the
- 45 sealing flap and the body of the envelope; (4) folding the sealing flap over and pressing it against the said section of thread; (5) severing the said section of thread from the continuous thread at a point beyond the end of the envelope so as to provide a protruding portion; and
- 50 (6) releasing the envelope so that it may be discharged from the rotor.

General organization

- 60 The various mechanisms of the machine are supported in a suitable framework which, as illustrated, includes housings 5 and 6 and cross members 7 and 8, the said framework being mounted upon a suitable base 9. The rotor 10 is fixed to a shaft 11 which is suitably journalled at its opposite ends in bearings 12, the latter being carried by the cross members 7 and 8. A plurality of envelope carrying units 13 are suitably secured to an annular flange 14 formed or provided on the rotor 10. In the embodiment illustrated, the units 13 are spaced 45° apart and the rotor 10 is caused to rotate step-by-step each time through an angle of 45° to successively position the units beneath an envelope magazine or rack 15 so that an en-

velope may be withdrawn from the said magazine and deposited upon one of the units during each pause of the rotor. The magazine 15 (Fig. 5) is mounted upon a cross rod 16 which is supported by arms 17 from a cross member 18. The magazine includes upper and lower guide rails 19 and 20 and a platform 21, the rails 20 and the said platform providing a continuous supporting surface for the envelopes. The rails 19 and 20 are inclined toward a resilient stop 22 which is supported from arms 23 by a cross rod 24. The lower end of the stop 22 cooperates with the forward edge of the platform 21 to provide a discharge opening through which the envelopes may be withdrawn from the magazine and deposited upon the units carried by the said rotor. To this end a pair of arms 25 is mounted upon a shaft 26. Each of said arms carries a finger 27, the said fingers lying at opposite sides of the stop 22. As the shaft 26 is rocked to move the arms 25 downwardly the fingers 27 are adapted to enter between the sealing flap and the body of the foremost envelope in the magazine and engage the fold provided by the flap and the body of the envelope, whereby as the fingers continue to move downwardly the envelope is withdrawn from the magazine. Movement of the fingers in the manner described is effected by a crank 28. The latter includes a body 29 which is formed or provided with an elongated slot 30. The body 29 is mounted upon the end of the main cam shaft 31 of the machine. The end of the cam shaft extends through the slot 30 and the body 29 is mounted upon the said end by a block 32 which is carried by the end of the shaft and which is slidably mounted for reciprocating movement in the slot 30. The block is suitably grooved at its opposite sides so as to provide guideways for the crank. The body 29 at one end is connected by a link 33 to an arm 34 which is carried by the shaft 26. At its opposite end the said body carries a roller 35 which fits in a cam groove 36 provided by a cam wheel 37, the said wheel being fixed to the cam shaft 31. It will be apparent that as the cam shaft 31 rotates the crank 29 will reciprocate, the reciprocating movement of the crank resulting in an oscillatory movement of the shaft 26 and the envelope feeding arms 25 carried thereby. An envelope in its passage from the magazine 15 to the envelope carrying unit therebeneath is guided by a curved plate 38 which is supported in cooperating relation with the feeding arms by a shaft 38a.

The cam wheel 37 carries a sprocket 39 (Fig. 6). The cam shaft 31 is driven by this sprocket from an auxiliary shaft 40 which carries a sprocket 41, the sprockets 39 and 41 being connected by a suitable chain 42. The auxiliary shaft 40 is connected to drive a shaft 43 by sprockets 45 and 46 and a suitable chain 47. The shaft 43 is connected by a belt 42a to the drive pulley of a motor 42, the pulley 43a constituting a part of a clutch 44. It will be apparent that when the clutch 44 is engaged the cam shaft 31 will be continuously rotated. In order to move the rotor 10 angularly step-by-step so as to enable positioning of the carrier units one at a time beneath the envelope magazine the cam shaft 31 carries a worm 48. The said worm is formed with a cam groove 49 which cooperates with a circular series of pins 50 mounted upon the rear face of the rotor 10. The leading and trailing ends 51 and 52 respectively, as best shown in Fig. 31, constitute the major portion of the groove. These ends of the groove are substantially straight and

are connected by a spiral portion 53. The pins 50 are engaged successively by the worm and are caused to traverse the cam groove, it being apparent that no movement is transmitted by the 5 worm to the rotor during the time that the pins are traversing the straight ends of the groove. In other words, at such times the rotor will remain stationary, movement being imparted to the rotor only during such times as the pins traverse the 10 spiral portion 53 of the groove. During those intervals that the rotor 10 is stationary it is locked against movement by the engagement between the pins and the groove. It will be noted that two of the pins 50 are at all times engaged by the cam 15 groove 49. The entrance to the leading end 51 of the cam groove is enlarged as at 54 while the exit from the trailing end of the groove is similarly enlarged as at 55. The spiral portion 53 of the groove is so located relative to the entrance and 20 exit ends thereof that as one of the pins 50a (Fig. 31) enters the exit portion 55 of the groove the next succeeding pin 50b enters the spiral portion 53 of the groove. As the rotor 10 is rotated by the movement of the pin 50b in the spiral portion of 25 the groove, the pin 50a passes out the exit 55 of the groove while the pin succeeding the pin 50b moves with the entrance 54 of the groove, it being understood that the rotor is stationary during the time required for the last mentioned pin to move 30 to the spiral portion of the said groove. The cam groove 49 is so formed that each movement of the rotor 10 is through an angle of 45°, an envelope carrying unit being located directly beneath the envelope magazine during the final part of each 35 such angular movement of the rotor and remaining in such position until the next succeeding pin is engaged by the spiral portion of the cam groove.

The envelopes, as best shown in Figure 8, are deposited by the envelope feed mechanism face 40 down upon the envelope carrying units. Each envelope carrying unit includes a body 56 (Figs. 9-21). The top wall of the body is formed with a pair of spaced elongated recesses 57 in which ejector fingers 58 normally lie. The free ends 45 59 of the fingers are turned up to provide stops against which the envelope is positioned by the feed mechanism. When the envelope is positioned against the ends 59 of the fingers as described the arm 25 of the feed mechanism is 50 moved upwardly to withdraw the fingers 27 from between the flap and the body of the envelope and are conditioned for depositing an envelope upon the next envelope carrying unit when the latter is moved into position.

55 *Envelope securing mechanism*

Means is provided whereby the envelope may be secured to the body 56 of the envelope carrying unit so that in the subsequent thread affixing 60 operations accurate cooperation between the unit and various associated mechanisms is obtained. To this end a gripping element 60 is fixed to one end of a shaft 61, there being one such shaft journaled at each side of the unit in a suitable 65 bearing 62. At its opposite end each shaft 61 carries a sector gear 63. Each of the said gears meshes with a companion sector gear 64 which is mounted upon a shaft 65 and which is formed with a tail piece 66. The tail pieces 66 of the 70 gears 64 are connected by a spring 67 which tends to move the gripping element 60 into engagement with the envelope. Means is provided whereby the gripping elements 60 may be actuated to enable the positioning of the envelope 75 upon the envelope carrying unit. To this end

each of the shafts 65 carries a knob 68. As the unit moves into an envelope receiving position beneath the envelope magazine 15 the knobs 68 move in front of a pair of operating elements 69 (Figs. 3, 23 and 24) which are carried by a shaft 70, the latter being suitably journaled in the side housings of the machine. The said shaft carries an arm 71 which is connected by a link 72 to one end 73 of a bell crank 74, the latter being freely mounted upon a shaft 75. The end 76 of the bell crank carries a roller 77 which fits in a cam groove 78 formed in a cam wheel 79, the latter being keyed to the cam shaft 31. The cam groove 79 is so formed that the operating elements 69 are held in their retracted position as the said unit comes to rest beneath the envelope magazine. Thereafter, prior to the deposit of an envelope from the magazine upon the said unit, the operating elements 69 are moved into engagement with the knobs 68 and the gripping elements 60 are moved to the position shown in Fig. 11 against the action of the spring 67. While the gripping elements are held in this position an envelope is deposited upon the unit beneath the gripping elements in the manner described. 100 Thereupon the cam 79 is operative to withdraw the elements 69 out of cooperation relation with the knobs 68 and permit the gripping element 60 under the influence of a spring 67 to engage the envelope and secure the latter upon the body of 105 the unit.

Means is provided whereby the envelope may be located at a predetermined position upon the body of said unit prior to the engagement of the gripping elements. To this end the body 56 110 carries at one side a stop 80 (Figs. 10 and 12). At the opposite side of the body an element 81 is loosely mounted upon a headed pin 82. The said pin carries a spring 83. One end of the spring is suitably secured to the head of the pin 115 while the other end of the spring engages the back of the element 81. The upper end of the said element extends above the top of the unit and is normally urged by the spring 83 in the direction of the stop 80 at the opposite side of 120 the body. The upper end of the element 81 is moved to the position shown in full lines in Fig. 12 prior to the deposit of an envelope upon the unit. To this end an arm 84 (Fig. 9) is fixed to the end of the shaft 65. The said arm carries 125 a pin 85 which projects in back of the lower end of the element 81. Hence as the knobs 68 are moved by the operating elements 69 to move the gripping elements 60 to their envelope receiving position, the pin 85 engages the lower end of 130 the element 81 and moves the upper end thereof to the position shown in full lines in Fig. 12. It will be apparent, therefore, that when the knobs 68 are released the pin 85 under the influence of the spring 67 will move away from the lower end of the element 81 and permit the upper end thereof to move the envelope toward and against the stop 80 before the envelope is engaged by the gripping elements. Thus the envelope is secured upon the body of the unit in a predetermined position prior to the thread affixing operations.

Flap opening mechanism

After an envelope is secured upon one of the 145 units 13 in the manner described the flap thereof is opened so that positioning of the thread which is to be secured to the envelope will be facilitated. To this end the unit 13 carries a finger 86 which is formed with a hooked end 87, the said finger 150

being held in spaced relation to the unit 13 with which it is associated when the said unit is in an envelope receiving position (see Fig. 5). With the finger 86 in this position the envelope which 5 is withdrawn from the magazine 15 may be arranged upon the unit in the position in which it is to be secured. The finger 86 is secured to an arm 88 which is pivotally mounted upon a pin 89. The arm 88 is mounted upon the said pin 10 between a pair of upstanding ribs 90 which are carried by a member 91, the said member being fixed to a shaft 92 which is mounted in bearing supports 93 formed or provided on the body of the unit. The shaft 92 is freely mounted in said 15 bearing supports. The member 91 carries a roller 94 which cooperates with a cam ring 95, the said ring being carried by the flared end of a member 96 which is secured at its reduced end to the cross member 7 of the machine (Fig. 8). 20 The roller 94 follows the cam ring 95, the roller being held in cooperating relation with the cam ring by a spring 97. One end of the spring is connected to a pin 98 carried by the member 91 while the opposite end of the spring is connected 25 to a pin 99 carried by the body of the unit. The arm 99 carries a tail piece 100 which is formed to provide shoulders 101 and 102, the said shoulders cooperating with a dog 103 which is pivotally mounted between the ribs 90 of the member 91 30 upon a pin 104. A spring 105 is connected at one end to a pin 106 carried by the dog and at its opposite end to a pin 107 carried by the arm 88, the said spring serving to maintain the dog 103 and the tail piece 100 in cooperating relation. 35 The parts are so designed that when an envelope carrying unit 13 is in an envelope receiving position relative to the magazine 15, the dog 103 engages the shoulder 101 of the tail piece 100 and the finger 86, therefore, as shown in Fig. 5 is held 40 away from the envelope carrying unit so that an envelope may be moved between the hooked end of the finger 86 and the body of the envelope carrying unit and deposited upon the latter. The shaft 26 by which the envelope feed arms 25 are 45 carried also carries an arm 108 (Fig. 5) which is arranged between the two arms 25. The arm 108 is so formed that as an envelope which has been withdrawn from the magazine 15 approaches the stops 59 of the envelope carrying 50 unit it engages the dog 103 (Fig. 8) and releases the latter from engagement with the shoulder 101 of the tail piece of the arm 88. Thereupon the hooked end of the finger 86 is moved by the spring 105 into engagement with the back of 55 the envelope. During the operation described the rotor 10 is stationary and the roller 94 cooperates with an elevated portion 95a of the cam 95. At a point just beyond the envelope receiving position the face of the cam falls away as at 109 60 (Fig. 33) to a lower level 110. The member 91, therefore, moves inwardly toward the rotor 10 as the envelope carrying unit is moved away from the envelope receiving position. During this movement of the said member the dog 103 65 moves into engagement with the shoulder 102 (Fig. 18) of the tail piece of the arm 88 and pivots the said arm about the pin 89. In other words, the finger 86 is moved downwardly and then outwardly. During this movement of the 70 said finger the hooked end 87 thereof first passes between the flap and the body of the envelope and then moves the flap to a position which, in the embodiment illustrated, is at an angle slightly less than 90° with respect to the body of the envelope. The parts assume this position as the

roller 94 reaches the bottom of the inclined portion 109 of the cam 95 and they are maintained in such position during the subsequent movement of the rotor through an angle of 45°.

80

Thread applying mechanism

An envelope having its flap open in the manner described is shown at 111 (Fig. 34) and as it is moved to the position occupied by the preceding envelope 112 is moved toward a section of a thread 113 in such a manner that the said section of thread is positioned adjacent the juncture of the flap and the body of the envelope between the said flap and body. The thread 113 to which a suitable adhesive is applied has already been positioned in this manner with respect to the envelope 112. At the station occupied by envelope 112, however, the thread is also secured to the envelope. Hence as the envelope 112 moves toward the position occupied by the preceding envelope 114 the section of the thread 113 which is to provide the opening thread for the envelope 111 is fed to the station from which the envelope 112 is moved away, the movements of the thread and envelope being so controlled that as the envelope 111 reaches the station occupied by the envelope 112 a succeeding section of the thread 113 lies along the juncture of the flap and the body of the envelope. The thread 113 may be unwound from a suitable spool (not shown) carried from the frame work of the machine. It is passed in succession through openings 115, 116 and 117 formed in a bracket 118 which is suitably supported upon the outer side of the housing 5 above a window 119 formed therein. In its movement between the openings 115 and 116 the thread is caused to pass beneath a resilient finger 120 which is carried by the bracket 118, thereby to tension that section of the thread between the finger 120 and the envelope 114. The opening 117 is formed in the lower end of an arm 121 of the bracket 118, the said arm extending into a receptacle 122 which provides a reservoir for the adhesive material with which the thread is to be coated or impregnated. From the opening 117 the thread passes upwardly over a roller 123. Excessive adhesive is removed from the thread by a resilient finger 124 which squeezes the thread against the roller, the pressure of the finger 124 upon the thread being controlled by an adjustable element 125. From the roller 123 the thread passes over a grooved wheel 126 which is carried by an arm 127. The latter is fixed to a shaft 128 which is journaled in suitable bearings carried by a bracket 130, the said bracket being supported upon the inner side of the housing 5 adjacent the window 119.

145

150

An arm 131 (Fig. 36) is fixed to the opposite end of the shaft 128, the said arm carrying a roller 132 which rides upon a cam 133. It will be apparent, therefore, that the position of the grooved wheel 126 is determined by the cam 133. The latter is fixed to and hence rotates continuously with the main cam shaft 31. The cam 133 is so formed that the wheel 126 is raised during each pause of the rotor and lowered during the rotary movements of the rotor. The mechanism described, therefore, enables the thread to be fed through the adhesive to the envelopes at a substantially uniform rate, the wheel 126 taking up the slack in the thread during the pauses in the movement of the rotor and giving up the slack during the angular movements of the rotor. In order to maintain the strain upon

the thread 113 at a minimum it is preferred that the wheel 123 be driven. To this end the said wheel is mounted upon the end of a shaft 134 which is journaled in suitable bearings provided by a bracket 135. The shaft 134 carries a gear 136 which meshes with a gear 137 carried by the main cam shaft 31 (Fig. 3). The thread 113 may be passed directly between the roller 123 and the finger 124 or it may, if desired, be wound about the roller 123 before being passed over the roller. In order to facilitate threading of the thread 113 through the various passages described the receptacle 122 is carried by a flanged support 138, the latter including a stem 139. The said stem fits in an opening 140 which is formed in a bracket 141, the latter being supported from the housing 5 of the machine. The stem 139 carries a cross pin 142 which is adapted to engage the top of the bracket 141 and support the receptacle 122 in the desired relation with the thread support bracket 118. At its opposite sides the opening 140 is enlarged to provide longitudinally extending slots 143, the slots being of the depth adequate to provide passages for the ends of the cross pin 142. It will be apparent, therefore, that the support 138 may be rotated so that the ends of the cross pin 142 register with the slots 143. When this is done the support 138 together with the receptacle 122 may be lowered to the position shown in dotted lines in Figure 34. With the support in this position the thread 113 may be conveniently arranged upon the thread support in the manner described. This construction has the further advantage that the receptacle 122 may be removed with facility when it is necessary to refill it or to remove its contents.

When the envelope 111 (Fig. 34) reaches the position occupied by the envelope 112 the thread 113 lies adjacent the juncture of the flap and the body of the envelope and the finger 86 occupies the position shown in Figures 18 and 19, the flap of the envelope being held open by the hooked end 87 of the finger. At this time the roller 94 of the member 91 is still contacting with the lower portion 110 of the cam 95, the roller occupying the position indicated in Fig. 33 as the 90° station.

Just beyond the point indicated as the 90° station the cam 95 is formed with a second portion 144, the said portion constituting the highest part of the cam. As the roller 94 rides up the elevated portion 144, the member 91 is pivoted upon the shaft 92 against the action of the spring 97. As the member 91 moves outwardly in this manner the dog 103, arm 88 and finger 86 carried by the latter are all pivoted as an assembly about the shaft 92 so that the finger 86 moves toward the envelope which is arranged upon the unit associated with the finger. During the first part of the movement of the member 91 the parts 103, 88 and 86 maintain the same relation in the assembly, that is to say the relation shown in Fig. 18. However, when the hooked end 87 of the finger 86 comes into contact with the envelope the remainder of the pivotal movement of the member 91 causes the finger 86 to move from between the flap and the body of the envelope to the position shown in Fig. 20. It will be apparent, therefore, that during the final movement of the member 91 when the hooked end 87 of the finger 86 is moving along the body of the envelope the member 91 and the dog 103 carried thereby continue to pivot about the shaft 92. The dog 103, therefore, rides over the shoulder 101

of the tail piece 100 to the position shown in Fig. 20.

Means is provided whereby after the hooked end 87 of the finger 86 is removed from between the flap and the body of the envelope, the flap is folded over and pressed upon the thread so as to effect the securement of the thread to the envelope. For this purpose the member 91 is formed or provided with a pair of oppositely extending arms 145 (Figs. 9, 10, 16 and 20). At their ends each of the said arms is formed with an opening 146 in which pins 147 loosely fit. The pins 147 are carried by the rearwardly extending arms 148 of a flap folder 149, the said folder being loosely mounted by means of the said arms upon the shaft 92. As best shown in Fig. 10 the folder is adapted to overlie the flap of the envelope the entire length of the envelope, it being noted that the folder is cut away at either side as at 150 so that when it is actuated accommodation will be provided for the ends 59 of the ejectors 58. The arms 148 of the folder, are, as best shown in Fig. 16, bifurcated and the pins 147 are preferably pivotally connected to the said arms by cross pins 151. The arms 145 fit loosely on the pins 147 and in order to transmit motion from the said arms to the arms 148, springs 152 are arranged upon the pins 147, the said springs being held under compression between the arms 145 and washers 153 carried by the said pins.

From the foregoing it will be apparent that as the roller 94 rides up the raised portion 144 of the cam 95 to withdraw the hooked end of the finger 86 from between the flap and the body of the envelope, the movement of the member 91 will be transmitted to arms 145. Thus, as the said arms are caused to move in the manner described the folder 149 is pivoted upon the flap of the envelope, the flap being folded over the thread upon the body of the envelope. The parts are so formed that as the flap is folded upon and against the body of the envelope further movement of the arms 145 is taken up by the springs 152. In other words during the final part of the movement of the arms 145, the folder 149 is forced tightly against the flap of the envelope to squeeze the thread between the flap and the body of the envelope. A portion of the adhesive carried by the thread, therefore, is applied to the envelope and firm securement of the thread thereto is insured.

The shaft 92 carries a blade 154 which is adapted to cooperate with a fixed blade 155 (Figs. 17 and 21), the blade 155 being adjustably supported upon the body 56 of the unit. During feeding movements of the thread the blade 154 occupies the position shown in Figure 17, the thread passing over the blade 155 beneath the blade 154. It will be noted that as the blade 154 is carried by the shaft 92 it will be moved toward the companion blade 155 as the folder 149 is actuated to fold the flap of the envelope upon the thread 113. The angular relation of the blade 154 to the shaft 92 is preferably such that the blade 154 cuts the thread between the envelope upon the unit with which the blade is associated and the preceding envelope during the final squeezing movement of the folder upon the thread. In other words, the blade 154 is adapted to sever the thread during the final movement of the member 91 at a time when the thread is actually secured to the envelope. In order to insure efficient cooperation between the stationary and movable blades of the thread severing mechanism, a spring 156 (Fig. 14) is

arranged upon the shaft 92 between the member 91 and one of the arms 148 of the folder. The spring 156 acts against the member 91 and the arm 148 to hold the movable blade 154 against 5 the companion stationary blade.

Envelope discharging mechanism

It will be apparent that upon the completion 10 of the thread affixing and severing operations, the envelope will occupy the 135° position, that is to say the position occupied by the envelope 114 (Fig. 34). At the next station, that is to say the 180° station the envelope is to be discharged. In order to enable this the cam 95 15 is formed with a second depression 157 (Fig. 33), which depression starts just beyond the 135° station. Hence as the envelope moves from the position occupied by the envelope 114 toward the 180° station, the roller 91 rides into the depression 157. At this time the dog 103 is 20 in engagement with the shoulder 101 of the tail piece 100. Hence as the roller 94 moves into the depression 157 the member 91 is pivoted about the axis of the shaft 92 and the finger 86 is 25 moved to the position shown in Fig. 8. With the finger in this position the envelope can be readily discharged. As the envelope carrying unit comes to a pause at the 180° station with the finger 86 in the position described, the operating 30 knobs 68 of the gripping elements 60 are positioned in front of a pair of arms 158, the said arms being mounted upon a shaft 159 (Fig. 3) supported between the housings 5 and 6 of the machine. Each of the arms as best shown in 35 Figs. 25 and 27 is formed or provided with a ball-shaped extension 160. An arm 161 is fixed to the shaft 159 and is connected by a link 162 to one end of a bell crank 163, the latter being 40 loosely mounted upon the shaft 75. At its opposite end the bell crank 163 carries a roller 164 which fits in a cam groove 165. The latter is formed in a cam wheel 166 which is fixed to the main cam shaft 31. The cam groove 165 is so 45 formed that while the envelope carrying unit pauses at the 180° station the shaft 159 is actuated to move the arms 158 into cooperating relation with the operating knobs 68 of the envelope gripping elements 60 and the latter are pivoted away from the envelope against the action of the 50 spring 67 to release the envelope.

With reference to Fig. 10 it will be noted that the envelope is positioned face down over the ejectors 58 which are arranged in the slots 57. The ejectors 58 are fixed to a shaft 167 which 55 is journaled in bearings 168 provided upon the body 56 by rearwardly extending ribs 169.

The fingers 58 are held in the recesses 57 by springs 170. One terminal portion 171 (Figs. 10 and 11) of each spring is secured to the pivoted 60 end of the associated finger while the other terminal portion 172 of the spring lies against the adjacent end of the body 56, it being noted that the said springs are held in cooperating relation with their respective fingers by means of washers 65 173 which are carried at the ends of the shaft. Between the bearings 168 the shaft 167 carries an arm 174 which is formed with a ball-shaped end 175, the said arm being fixed to the shaft 167. As an envelope carrying unit is moved to the 180° 70 station, that is to say the station at which the envelope is to be discharged and the operating knobs 68 of the gripping elements 60 are moved into cooperating relation with the arms 158 by which the gripping elements are operated to release 75 the envelope, the ball-shaped end 175 of

the arm 174 is positioned in front of a ball-shaped extension 176 (Figs. 26 to 29 inclusive) which is carried by an arm 177. The latter is loosely mounted upon the shaft 159 and it is connected by a yoke 178 to a second arm 179 which is also loosely mounted upon the shaft 159. The arm 179 is connected by a link 180 to the lower end of a bell crank 181 which is loosely mounted upon the shaft 75. The opposite end of the bell crank 181 carries a roller 182 which fits in a cam groove 183 formed in a cam wheel 184. The said wheel is fixed to the main cam shaft 31 and the cam groove 183 is so formed that while an envelope carrying unit pauses at the discharge stations and after the envelope securing elements 60 have been operated to release the envelope, the arm 177 is moved into cooperating relation with the operating arm 174 of the ejector fingers 58. As the arm 177 moves against the end of the arm 75 the shaft 167 is rotated in the bearings 168 to move the ejector fingers 58 out of the recesses 57 to the position shown in Fig. 8. The said fingers, therefore, as they move out of the recesses 57 engage the envelope and eject it from the unit, the envelope falling by gravity upon an endless conveyor 185 which is located at the envelope discharge station. The envelope may be carried away from the machine by the conveyor 185 and dried in any suitable manner if this is desired. The depression 157 in the cam 95 extends from 105 the 180° or discharge station to a point just in advance of the station at which the envelopes are deposited upon the envelope carrying units. From a point just in advance of this station the cam face rises from the depression 157 to the elevated portion 95a, the said portion as shown by the construction line 187 being lower than the elevated portion 144 of the cam. As the roller 94 of the member 91 reaches the top of the elevated portion 95a the flap opening finger 86 is returned 115 to the position shown in Fig. 5, that is to say the envelope receiving position.

From the foregoing it will be apparent that as each envelope passes through the machine the flap thereof is opened and a section of a continuous thread to which an adhesive is applied is positioned and secured adjacent the juncture of the flap and the body of the envelope, the securing of the thread being effected by folding the flap upon the thread and squeezing the latter 125 between the flap and the body of the envelope. As the envelope moves toward the discharge station it feeds a succeeding section of the thread adjacent the juncture of the flap and the body of the next succeeding envelope. After the succeeding section of thread has been secured to the succeeding envelope the connected sections of thread are severed. Each envelope 188 (Fig. 22) which is discharged from the rotor has secured thereto an opening thread 189, one end 190 of the 135 said thread protruding beyond the end of the envelope so that when the flap is sealed the envelope may be opened by pulling the protruding end transversely of the fold provided by the flap and the body of the envelope. In this connection it is 140 understood, of course, that the parts may be so designed that either or both ends of the opening thread may protrude.

As shown, and preferred, the various mechanisms at each station on the rotor are incorporated in a removable unit. This has the advantage that any one of the units may be quickly replaced in the event that any of the parts thereof are injured or fail to function in the proper manner. It is to be understood, of course, that 150

the number of envelope receiving stations may be varied as desired, the number shown being by way of example only.

5 *Automatic clutch release mechanism*

The connection of the shaft 43 to the motor 42 is, as described, through the medium of the clutch 44. The latter includes a control lever 191 which is mounted upon a shaft 192 (Figs. 1, 10 3, 39 and 40), the said shaft being supported from the housing 6 of the machine. A sleeve 193 fits over the shaft 192 and is adapted to hold the hub 194 of the control lever at the desired point on the shaft 192. A pair of depending ears 15 195 and 196 are formed upon the hub 194, the ear 195 being connected by a spring 197 to a convenient part of the housing 6. The spring 197 is adapted to urge the clutch lever 191 to its inoperative position. The ear 196 of the hub 194 20 is connected by a link 198 to elements 199 and 199a of the clutch 44. The said elements are connected to cooperating clutch members 200 and 200a, respectively. The latter are formed with opposed beveled shoulders 201, whereby as 25 they are caused to rotate in opposite directions they are forced apart. As the said members are held against axial movement in one direction by a collar 202, the member 200a is caused to move axially of the shaft 43 toward the pulley 43a. 30 This movement is utilized in connection with pins 203 which are carried by the clutch member 200a to secure the pulley 43a to the shaft 43. The clutch 44 may be of any conventional construction and hence this general description is adequate 35 for the purpose in view. It will be apparent, therefore, that the clutch may be engaged to connect the main cam shaft to power by moving the clutch lever 191 downwardly. In order to maintain the engagement of the clutch 40 the hub 94 of the control lever carries a disc 204. The said disc is formed with a series of teeth 205 which cooperate with a dog 206, the latter being carried by a shaft 207 which is carried by the housing 6. When the control lever 191 is moved 45 downwardly in the direction of the arrow (Fig. 39) to effect the engagement of the clutch 44 the dog 206 engages one of the teeth 205 of the disc 204 and the lever is held thereby in the clutch engaging position.

50 Means is provided whereby the clutch 44 is automatically released in the event that the envelope feed mechanism fails to deposit an envelope upon the envelope carrying units at the proper time. To this end the body 56 of each of the said units is formed with a depression 208 (Figs. 10, 12 and 13). The depression lies directly in the path of movement of the finger 86 and is large enough to permit the hooked end of the finger to enter it. In the normal operation of the machine the envelope is deposited upon the unit and hence covers the depression 208. The envelope, therefore, prevents the finger from entering the depression. In the event, however, that the envelope feed mechanism fails to deposit an envelope upon the unit the hooked end of the finger 86 will enter the depression when the roller 94 enters the depression 110 of the cam 95. The arm 38 carries a second tail piece 209 which is adapted to engage a contact member 210 (Fig. 39) in the event that the finger 86 enters the depression 208, the said contact being supported on but insulated from the frame of the machine. The contact 210 is connected to one side of the secondary winding of a transformer 211, the opposite side of the secondary winding

being connected by a wire 212 to one terminal of a solenoid 213. The opposite side of the solenoid 213 is grounded to the machine by a wire 214 while the tail piece 209 is also grounded. Hence upon engagement of the tail piece 209 with the contact 210 the solenoid 213 is energized. An armature 215 is arranged within the solenoid 213 and is adapted to be lifted when the solenoid is energized. The said armature is connected by a link 216 to the free end of an arm 217, the latter being loosely mounted upon the shaft 207. The arm 217 carries a pin 218 which extends beneath the dog 206, the said pin being supported below and in spaced relation to the dog when the solenoid 213 is de-energized. Upon energization of the solenoid the armature 215 moves upwardly and carries the free end of the arm 217 with it. The pin 218 lifts the dog 206 and releases the disc 204. Upon the release of the disc 204 the spring 197 is operative to release the clutch 44, the lever 191 being returned to the upper limit of its range of movement by the said spring. It will be apparent, therefore, that upon the failure of the envelope feed mechanism to deposit an envelope upon an envelope carrying unit at the proper time, the solenoid 213 will be energized to disengage the clutch 44. The main cam shaft, therefore, will be disconnected from power as will be the various associated mechanisms. In order to insure immediate stopping of the main cam shaft 100 31 and associated mechanisms upon release of the clutch 44, the disc 204 is adapted to cooperate with a lever 219 which is supported for angular movement from the adjacent housing 6 by a stub shaft 220. At one end the lever 219 carries a 105 roller 221 which engages the periphery of the disc 204 while at its opposite end the said lever carries a brake shoe 222. The latter cooperates with a brake drum 223 which is carried by the shaft 43. The shoe 222 is urged against the drum 110 223 by a spring 224 which is connected at one end under tension to an ear 225 of the lever 219 and at its opposite end to a convenient part of the framework of the machine. The disc 204 is formed with a notch 226 in which the roller 221 115 is positioned when the clutch 44 is disengaged. The said notch permits the spring 224 to hold the brake shoe 222 against the brake drum. However, when the clutch lever 191 is moved downwardly to engage the clutch, the disc 224 is operative 120 during the initial part of the downward movement of the member 191 to engage the roller 221 and move the shoe 222 out of engagement with the brake drum 223. The motor 42, therefore, is permitted to drive the cam shaft 31 and 125 associated mechanisms, the clutch being held in engagement by the dog 26 in the manner described until the said dog is released. It will be apparent from the foregoing that upon energization of the solenoid 213, the clutch being in engagement, the spring 197 is operative to disengage the clutch, the notch 204 moving toward the roller 221 as the disc 204 moves angularly about the shaft 192. As the roller 221 moves into the notch 226 the brake is applied in the manner 130 described, the clutch 44 having been released prior to the entry of the roller 221 into the notch.

135 *Operation of machine*

In order to start the machine the rotor 10 is 140 adjusted by means of a hand wheel 230 which is carried by the auxiliary shaft 40 until one of the envelope carrying units is moved to an envelope receiving position, that is to say to the position beneath the envelope feed mechanism. 145 150

An envelope is then deposited by hand upon the unit and as the rotor 10 is moved by means of the hand wheel 230 in the direction that it normally rotates, the envelope is secured upon the unit by the gripping elements 60. The envelope carrying unit is then moved to the 90° station and while the flap of the envelope is held open by the finger 86 the thread 113 is positioned manually adjacent the juncture of the flap and the body 10 of the envelope. While the thread is arranged in this position the rotor 10 is moved toward the 135° station by means of the hand wheel 230. At the outset of this movement the flap of the envelope is folded over and squeezed upon the 15 thread. Further movement, therefore, of the envelope will feed the succeeding sections of the thread in the manner desired. The machine may then be started by engaging the clutch 44. Thereafter the envelopes are deposited upon the 20 rotor by the envelope feed mechanism and the thread affixing operations are performed automatically in the manner described.

We claim as our invention:

1. In a machine for affixing opening threads to 25 envelopes, the combination of a rotor, means for positioning an envelope upon said rotor in such a manner that as the said rotor rotates the envelope is moved lengthwise, means for opening the flap of said envelope, means for positioning a thread to which an adhesive is applied adjacent the juncture of the flap and the body of the envelope and means for folding the flap upon said 30 thread, whereby to secure the thread to the envelope.

2. In a machine for affixing opening threads to 35 envelopes, the combination of a rotor, means for positioning an envelope upon said rotor in such a manner that as the said rotor rotates the envelope is moved lengthwise, means for opening the flap of said envelope, means for positioning a thread to which an adhesive is applied adjacent the juncture of the flap and the body of the envelope and means for folding the flap upon the 40 thread and for squeezing the thread between said flap and body, whereby the securement of the 45 thread to the envelope is effected.

3. In a machine for affixing opening threads to 50 envelopes, the combination of a rotor, means for causing the rotor to rotate step-by-step, means for positioning an envelope upon said rotor in such a manner that as the said rotor rotates the envelope is moved lengthwise, means for opening the flap of said envelope, means for positioning a thread to which an adhesive is applied adjacent the juncture of the flap and the body of the envelope and means for folding the flap upon the 55 thread and for squeezing the thread between said flap and body, whereby the securement of the thread to the envelope is effected.

4. In a machine for affixing opening threads to 60 envelopes, the combination of a rotor, means for causing the rotor to rotate step-by-step, an envelope magazine, means operative during a pause of said rotor to withdraw an envelope from said magazine and deposit it upon said rotor, means for positioning a thread to which an adhesive is applied adjacent the juncture of the flap and the body of the envelope and means for pressing the said thread against said envelope, whereby its securement to the latter is effected.

5. In a machine for affixing opening threads to 65 envelopes, the combination of a rotor, means for causing the rotor to rotate step-by-step, an envelope magazine, means operative during a pause of said rotor to withdraw an envelope from

said magazine and deposit it upon said rotor in such a manner that as the said rotor rotates the envelope is moved lengthwise, means for positioning a thread to which an adhesive is applied adjacent the juncture of the flap and the body 80 of the envelope and means for pressing said thread against said envelope, whereby its securement to the latter is effected.

6. In a machine for affixing opening threads to 85 envelopes, the combination of a rotor, means for causing the rotor to rotate step-by-step, an envelope magazine, means operative during a pause of said rotor to withdraw an envelope from said magazine and deposit it upon said rotor, means for opening the flap of said envelope, means 90 for positioning a thread to which an adhesive is applied adjacent the juncture of the flap and the body of the envelope and means for pressing said thread against said envelope, whereby its securement to the latter is effected.

7. In a machine for affixing opening threads to 95 envelopes, the combination of a rotor, means for causing the rotor to rotate step-by-step, an envelope magazine, means operative during a pause of said rotor to withdraw an envelope from said magazine and deposit it upon said rotor in such a manner that as the said rotor rotates the envelope is moved lengthwise, means for opening the flap of said envelope, means for positioning a thread to which an adhesive is applied adjacent 100 the juncture of the flap and the body of the envelope and means for pressing the thread against said envelope, whereby its securement to the latter is effected.

8. In a machine for affixing opening threads to 110 envelopes, the combination of a rotor, means for causing the rotor to rotate step-by-step, an envelope magazine, means operative during a pause of said rotor to withdraw an envelope from said magazine and deposit it upon said rotor, means for opening the flap of said envelope, means for positioning a thread to which an adhesive is applied adjacent 115 the juncture of the flap and the body of the envelope and means for squeezing the thread between said flap and body, whereby its securement to the envelope is effected.

9. In a machine for affixing opening threads to 120 envelopes, the combination of a rotor, means for causing the rotor to rotate step-by-step, an envelope magazine, means operative during a pause of said rotor to withdraw an envelope from said magazine and deposit it upon said rotor in such a manner that as the said rotor rotates the envelope is moved lengthwise, means for opening the flap of said envelope, means for positioning a thread to which an adhesive is applied adjacent 125 the juncture of the flap and the body of the envelope and means for squeezing the thread between said flap and body, whereby its securement to the envelope is effected.

10. In a machine for affixing opening threads to 130 envelopes, the combination of a rotor, means for positioning envelopes upon said rotor in such a manner that as the said rotor rotates the envelopes are moved lengthwise, means for positioning a section of a continuous thread to which an adhesive is applied adjacent the juncture of the flap and the body of an envelope, means for 135 pressing said section of thread against said envelope so that it is secured thereto, whereby as the said envelope is advanced by said rotor a second section of said thread is moved to a position adjacent the juncture of the flap and the body of 140

145 envelope so that it is secured thereto, whereby as the said envelope is advanced by said rotor a second section of said thread is moved to a position adjacent the juncture of the flap and the body of 150

- the next succeeding envelope and means for pressing said second section of thread against said succeeding envelope so that it is secured thereto.
- 5 11. In a machine for affixing opening threads to envelopes, the combination of a rotor, means for positioning envelopes upon said rotor so that they are caused to move lengthwise as said rotor rotates, means for positioning a section of a thread to which an adhesive is applied adjacent the juncture of the flap and the body of an envelope, means for pressing said section against said envelope so that it is secured thereto, means for opening the flap of the next succeeding envelope, said first mentioned envelope being adapted as it is advanced by said rotor to feed a succeeding section of said thread adjacent the juncture of the flap and the body of said succeeding envelope and means for pressing said second section of thread against said succeeding envelope so that it is secured thereto. 80
- 10 12. In a machine for affixing opening threads to envelopes, the combination of a rotor, means for positioning envelopes upon said rotor so that they are caused to move lengthwise as the said rotor rotates, means for positioning a section of a thread to which an adhesive is applied adjacent the juncture of the flap and the body of an envelope, means for pressing said section against said envelope so that it is secured thereto, means for opening the flap of the next succeeding envelope, said first mentioned envelope being adapted as it is advanced by said rotor to feed a succeeding section of said thread adjacent the juncture of the flap and the body of said succeeding envelope and means for squeezing said succeeding section of thread between the flap and the body of said succeeding envelope, whereby to secure said succeeding section of thread to said 85 envelope. 90
- 15 13. In a machine for affixing opening threads to envelopes, the combination of a rotor, means for positioning envelopes upon said rotor so that they are caused to move lengthwise as the said rotor rotates, means for positioning a section of a thread to which an adhesive is applied adjacent the juncture of the flap and the body of an envelope, means for pressing said section of thread against said envelope so that it is secured thereto, means for opening the flap of the next succeeding envelope, said first mentioned envelope being adapted as it is advanced by said rotor to feed a succeeding section of said thread adjacent the juncture of the flap and the body of said succeeding envelope, means for squeezing said succeeding section of thread between the flap and the body of said succeeding envelope and means for severing the thread between said first mentioned and succeeding envelopes after said thread 95 has been secured to the latter. 100
- 20 14. In a machine for affixing opening threads to envelopes, the combination of a rotor, an envelope magazine, means for withdrawing an envelope from said magazine and positioning it on said rotor, means for positioning a thread to which an adhesive is applied adjacent the juncture of the flap and the body of said envelope and means carried by said rotor for pressing said flap upon said thread, whereby the latter is secured to said envelope. 105
- 25 15. In a machine for affixing opening threads to envelopes, the combination of a rotor, an envelope magazine, means for withdrawing an envelope from said magazine and positioning it on said rotor, means for positioning a thread to which an adhesive is applied adjacent the juncture of the flap and the body of each envelope, means for pressing said thread against each envelope so that it is secured thereto, a motor for driving said carrier and operating said means first mentioned and means operative upon the failure of said means first mentioned to position an envelope upon said carrier at the proper point for stopping said carrier. 110
- 30 16. In a machine for affixing opening threads to envelopes, the combination of a rotor, an envelope magazine, means for withdrawing envelopes from said magazine and positioning them at spaced intervals upon said rotor, means for positioning an opening thread to which an adhesive is applied adjacent the juncture of the flap and the body of each envelope, means for pressing said thread against each envelope so that it is secured thereto, a motor for driving said carrier and operating said means first mentioned and means operative upon the failure of said means first mentioned to position an envelope upon said carrier at the proper point for stopping said carrier. 115
- 35 17. In a machine for affixing opening threads to envelopes, the combination of a rotor, an envelope magazine, means for withdrawing envelopes from said magazine and positioning them at spaced intervals upon said rotor, means for positioning an opening thread to which an adhesive is applied adjacent the juncture of the flap and the body of each envelope, means for pressing said thread against each envelope so that it is secured thereto, a motor for driving said rotor and for operating said means first mentioned and means operative upon the failure of said means first mentioned to position an envelope upon said rotor at the proper point for stopping said rotor. 120
- 40 18. In a machine for affixing opening threads to envelopes, the combination of a rotor which is adapted to provide a plurality of envelope receiving stations, an envelope magazine, means for rotating said rotor to move said stations successively into an envelope receiving position with relation to said magazine, means for withdrawing envelopes from said magazine and depositing them upon said rotor at said stations when they are moved to an envelope receiving position, means at each of said stations for securing an envelope to said rotor, means for positioning a thread to which an adhesive is applied adjacent the juncture of the flap and the body of each envelope, means at each station for pressing said thread against the envelope at that station so as to secure it to the envelope and means for releasing the envelope securing means of a station after the thread is secured to the envelope at said station. 125
- 45 19. In a machine for affixing opening threads to envelopes, the combination of a rotor, which is adapted to provide a plurality of envelope receiving stations, an envelope magazine, means for rotating said rotor step-by-step to move said stations successively into an envelope receiving position with relation to said magazine, means for withdrawing envelopes from said magazine and depositing them upon said rotor at said stations when they are moved to an envelope receiving position, means at each station for securing an envelope to said rotor, means for positioning a thread to which an adhesive is applied adjacent the juncture of the flap and the body of each envelope, means at each station for pressing said thread against the envelope at said station so as to secure the thread to the envelope and means for releasing the envelope securing means of each station after the thread is secured to the envelope at said station. 130
- 50 140
- 55 145
- 60 150

- moved to such position, means at each station for securing an envelope to said rotor, means at each station for opening the flap of an envelope, means for feeding a section of a continuous 5 thread to which an adhesive is applied adjacent the juncture of the flap and the body of each envelope, means for squeezing such a section of thread between said flap and body of each envelope so as to secure the thread to the envelope, 10 means at each station for severing from the continuous thread the section thereof which is to provide the opening thread for the envelope at said station and means for releasing the envelope securing means of a station after the 15 thread is secured to the envelope at said station. 34. In a machine for affixing opening threads to envelopes, the combination of a rotor which is adapted to provide a plurality of envelope receiving stations, an envelope magazine, means 20 for rotating said rotor to move said envelope receiving stations successively to an envelope receiving position with relation to said magazine, means for withdrawing envelopes from said magazine and depositing them upon said rotor as said 25 stations are moved to such position, means at each station for securing an envelope to said rotor, means for positioning a thread to which an adhesive is applied adjacent the juncture of the flap and the body of each envelope, means at each station for squeezing the thread between the flap and body of the envelope at said station so as to secure the thread to the envelope, means for releasing the securing means of a station after the 30 thread is secured to the envelope at said station, 35 ejecting means at each station and means for operating the ejecting means at each station upon completion of the thread affixing operations. 35. In a machine for affixing opening threads to envelopes, the combination of a rotor which is adapted to provide a plurality of envelope receiving stations, an envelope magazine, means for rotating said rotor step-by-step to move said stations successively into an envelope receiving position with relation to said magazine, means 40 for withdrawing envelopes from said magazine and depositing them upon said rotor as said stations are moved to such position, means at each station for securing an envelope to said rotor, means at each station for opening the flap of an envelope, means 45 for positioning a thread to which an adhesive is applied adjacent the juncture of the flap and the body of each envelope, means at each station for pressing the thread against the envelope at said station so as to secure the thread to the envelope, means for releasing the envelope securing means of a station after the opening thread is secured to the envelope at said station, 50 ejecting means at each station and means for operating the ejecting means at each station upon completion of the thread affixing operations. 36. In a machine for affixing opening threads to envelopes, the combination of a rotor which is adapted to provide a plurality of envelope receiving stations, an envelope magazine, means for rotating said rotor to move said stations successively to an envelope receiving position with relation to said magazine, means for withdrawing envelopes from said magazine and depositing them upon said rotor as said stations are moved to such position, means at each station for securing an envelope to said rotor, means at each station for opening the flap of an envelope, means 55 for positioning a thread to which an adhesive is applied adjacent the juncture of the flap and the body of each envelope, means at each station for pressing the thread against the envelope at said station so as to secure the thread to the envelope, means for releasing the envelope securing means of a station after the opening thread is secured to the envelope at said station, 60 ejecting means at each station and means for operating the ejecting means at each station upon completion of the thread affixing operations. 37. In a machine for affixing opening threads to envelopes, the combination of a rotor which is adapted to provide a plurality of envelope receiving stations, an envelope magazine, means for rotating said rotor step-by-step to move said stations successively to an envelope receiving position with relation to said magazine, means for withdrawing envelopes from said magazine and depositing them upon said rotor as said stations are moved to such position, means at each station for securing an envelope to said rotor, means at each station for positioning a thread to which an adhesive is applied adjacent the juncture of the flap and the body of each envelope, means at each station for squeezing the thread between the flap and body of the envelope at said station so as to secure the thread to the envelope, means for releasing the securing means of a station after the thread is secured to the envelope at said station, 65 ejecting means at each station and means for operating the ejecting means at each station upon completion of the thread affixing operations. 38. In a machine for affixing opening threads to envelopes, the combination of a rotor which is adapted to provide a plurality of envelope receiving stations, an envelope magazine, means for rotating said rotor to move said stations successively to an envelope receiving position with relation to said magazine, means for withdrawing envelopes from said magazine and depositing them upon said rotor as said stations are moved to such position, means at each station for securing an envelope to said rotor, means at each station for opening the flap of an envelope, means 70 for positioning a thread to which an adhesive is applied adjacent the juncture of the flap and the body of each envelope, means at each station for pressing the thread against the envelope at said station so as to secure the thread to the envelope, means for releasing the envelope securing means of a station after the opening thread is secured to the envelope at said station, ejecting means at each station and means for operating the ejecting means at each station upon completion of the thread affixing operations. 39. In a machine for affixing opening threads to envelopes, the combination of a rotor which is adapted to provide a plurality of envelope receiving stations, an envelope magazine, means for rotating said rotor step-by-step to move said stations successively into an envelope receiving position with relation to said magazine, means for withdrawing envelopes from said magazine and depositing them upon said rotor as said stations are moved to such position, means at each station for securing an envelope to said rotor, means at each station for opening the flap of an envelope, means 75 for positioning a thread to which an adhesive is applied adjacent the juncture of the flap and the body of each envelope, means at each station for pressing the thread against the envelope at said station so as to secure the thread to the envelope, means for releasing the envelope securing means of a station after the opening thread is secured to the envelope at said station, ejecting means at each station and means for operating the ejecting means at each station upon completion of the thread affixing operations. 40. In a machine for affixing opening threads 80 85 90 95 100 105 110 115 120 125 130 135 140 145 150

- to envelopes, the combination of a rotor which is adapted to provide a plurality of envelope receiving stations, an envelope magazine, means for rotating said rotor to move said stations 5 successively to an envelope receiving position with relation to said magazine, means for withdrawing envelopes from said magazine and depositing them upon said rotor as said stations are moved to such position, means at each station for securing an envelope to said rotor, means at each station for opening the flap of an envelope, means for positioning a thread to which an adhesive is applied adjacent the juncture of the flap and the body of each envelope, means at each station 10 for squeezing the thread between the flap and body of the envelope at said station so as to secure the thread to the envelope, means for releasing the envelope securing means of a station after the thread is secured to the envelope at said 15 station, ejecting means at each station and means for operating the ejecting means of each station upon completion of the thread affixing operations.
41. In a machine for affixing opening threads to envelopes, the combination of a rotor which is adapted to provide a plurality of envelopes receiving stations, an envelope magazine, means for rotating said rotor step-by-step to move said stations successively to an envelope receiving position with relation to said magazine, means for withdrawing envelopes from said magazine and depositing them upon said rotor as said stations are moved to such position, means at each station for securing an envelope to said rotor, means at each station for opening the flap of an envelope, means 20 for positioning a thread to which an adhesive is applied adjacent the juncture of the flap and the body of each envelope, means at each station for squeezing the thread between the flap and body of the envelope at said station so as to secure the thread to the envelope, means for releasing the envelope securing means of a station after the thread is secured to the envelope at said station, ejecting means at each station and means for operating the ejecting means at each station upon completion of the thread affixing operations.
42. In a machine for affixing opening threads to envelopes, the combination of a rotor which is adapted to provide a plurality of envelope receiving stations, an envelope magazine, means for rotating said rotor to move said stations successively into an envelope receiving position with relation to said magazine, means for withdrawing envelopes from said magazine and depositing them upon said rotor when said stations are moved to such position, means at each station for securing an envelope to said rotor, means for feeding a section of a continuous thread to which an adhesive is applied adjacent the juncture of the flap and the body of each envelope, means at each station for pressing such a section of thread against the envelope at said station so as to secure the thread to the envelope, means at each station for severing from the continuous thread the section thereof which is to provide the opening thread for the envelope at said station, means for releasing the envelope securing means of a station after the thread is secured to the envelope at said station, ejecting means at each station and means for actuating the ejecting means of a station when the securing means at said station is released at the completion of the thread affixing operations.
43. In a machine for affixing opening threads to envelopes, the combination of a rotor which is adapted to provide a plurality of envelope receiving stations, an envelope magazine, means for rotating said rotor step-by-step to move said stations successively to an envelope receiving position with relation to said magazine, means for withdrawing envelopes from said magazine and depositing them upon said rotor when said stations are moved to such position, means at each station for securing an envelope to said rotor, means for feeding a section of a continuous thread to which an adhesive is applied adjacent the juncture of the flap and the body of each envelope, means at each station for pressing such a section of thread against the envelope at said station so as to secure the thread to the envelope, means at each station for severing from the continuous thread the section thereof which is to provide the opening thread for the envelope at said station, means for releasing the envelope securing means of a station after the thread is secured to the envelope at said station, ejecting means at each station and means for actuating the ejecting means of a station when the securing means at such station is released at the completion of the thread affixing operations.
44. In a machine for affixing opening threads to envelopes, the combination of a rotor which is adapted to provide a plurality of envelope receiving stations, an envelope magazine, means for rotating said rotor to move said stations successively to an envelope receiving position with relation to said magazine, means for withdrawing envelopes from said magazine and depositing them upon said rotor when said stations are moved to such position, means at each station for securing an envelope to said rotor, means for feeding a section of a continuous thread to which an adhesive is applied adjacent the juncture of the flap and the body of each envelope, means at each station for squeezing such a section of thread between the flap and body of the envelope at said station so as to secure the said section to the envelope, means at each station for severing from the continuous thread the section thereof which is to provide the opening thread for the envelope at said station, means for releasing the envelope securing means of a station after the thread is secured to the envelope at said station, ejecting means at each station and means for actuating the ejecting means of a station when the securing means at said station is released at the completion of the thread affixing operations.
45. In a machine for affixing opening threads to envelopes, the combination of a rotor which is adapted to provide a plurality of envelope receiving stations, an envelope magazine, means for rotating said rotor step-by-step to move said stations successively to an envelope receiving position with relation to said magazine, means for withdrawing envelopes from said magazine and depositing them upon said rotor when said stations are moved to such position, means at each station for securing an envelope to said rotor, means for feeding a section of a continuous thread to which an adhesive is applied adjacent the juncture of the flap and the body of each envelope, means at each station for squeezing such a section of thread between the flap and body of the envelope so as to secure the said section to the envelope, means at each station for severing from the continuous thread the section thereof which is to provide the opening thread for the envelope at said station, means for releasing the securing means of a station after the thread is secured to the envelope at said station, ejecting means at each station and means for actuating the ejecting means of a station when the securing means at said station is released at the completion of the thread affixing operations.

tion when the securing means at said station is released at the completion of the thread affixing operations.

46. In a machine for affixing opening threads to envelopes, the combination of a rotor which is adapted to provide a plurality of envelope receiving stations, an envelope magazine, means for rotating said rotor to move said stations successively to an envelope receiving position with relation to said magazine, means for withdrawing envelopes from said magazine and depositing them upon said rotor when said stations are moved to such position, means at each station for securing an envelope to said rotor, means at each station for opening the flap of an envelope, means for feeding a section of a continuous thread to which an adhesive is applied adjacent the juncture of the flap and the body of each envelope, means at each station for pressing such a section of thread against the envelope at said station so as to secure the thread to the envelope, means at each station for severing from the continuous thread the section thereof which is to provide the opening thread for the envelope at said station, means for releasing the envelope securing means of a station after the opening thread is secured to the envelope at said station, ejecting means at each station and means for actuating the ejecting means of a station when the securing means at said station is released upon the completion of the thread affixing operations.

47. In a machine for affixing opening threads to envelopes, the combination of a rotor which is adapted to provide a plurality of envelope receiving stations, an envelope magazine, means for rotating said rotor step-by-step to move said stations successively to an envelope receiving position with relation to said magazine, means for withdrawing envelopes from said magazine and depositing them upon said rotor when said stations are moved to such position, means at each station for securing an envelope to the rotor, means for feeding a section of a continuous thread to which an adhesive is applied adjacent the juncture of the flap and the body of each envelope, means at each station for pressing such a section of thread against the envelope at said station, so as to secure the said section to the envelope, means at each station for severing from the continuous thread the section thereof which is to provide the opening thread for the envelope at said station, means for releasing the envelope securing means of a station after the thread is secured to the envelope at said station, ejecting means at each station and means for actuating the ejecting means of a station when the securing means at said station is released at the completion of the thread affixing operations.

48. In a machine for affixing opening threads to envelopes, the combination of a rotor which is adapted to provide a plurality of envelope receiving stations, an envelope magazine, means for rotating said rotor to move said stations successively to an envelope receiving position with relation to said magazine, means for withdrawing envelopes from said magazine and depositing them upon said rotor when the stations are moved to such position, means at each station for opening the flap of an envelope, means for feeding a section of a continuous thread to which an adhesive is applied adjacent the juncture of the flap and the body of each envelope, means at each station for squeezing such a section of thread between the flap and body of the envelope when the latter is positioned adjacent the juncture of the flap and the body of said envelope, said gripping means being released upon completion of the thread affixing operations to enable the removal of the envelope from the said unit.

49. In a machine for affixing opening threads

lope at said station so as to secure the said section to the envelope, means at each station for severing from the continuous thread the section thereof which is to provide the opening thread for the envelope at said station, means for releasing the envelope securing means of a station after the thread is secured to the envelope at said station, ejecting means at each station and means for actuating the ejecting means of a station when the securing means at said station is released at the completion of the thread affixing operations.

50. In a machine for affixing opening threads to envelopes, the combination of a rotor which is adapted to provide a plurality of envelopes receiving stations, an envelope magazine, means for rotating said rotor step-by-step to move said stations successively to an envelope receiving position with relation to said magazine, means for withdrawing envelopes from said magazine and depositing them upon said rotor when said stations are moved to such position, means at each station for securing an envelope to said rotor, means at each station for opening the flap of an envelope, means for feeding a section of a continuous thread to which an adhesive is applied adjacent the juncture of the flap and the body of each envelope, means for squeezing such a section of thread between the flap and body of the envelope at said station so as to secure the said section to the envelope, means at each station for severing from the continuous thread the section thereof which is to provide the opening thread for the envelope at said station, for releasing the envelope securing means of a station after the thread is secured to the envelope at said station, ejecting means at each station and means for actuating the ejecting means of a station when the securing means at said station is released at the completion of the thread affixing operations.

51. In a machine for affixing opening threads to envelopes, the combination of an envelope magazine, a rotor, an envelope carrying unit mounted on said rotor and adapted to be moved thereby into an envelope receiving position with relation to said magazine, means for withdrawing an envelope from said magazine and depositing it upon said unit, said unit including gripping means for securing the envelope upon said unit and a squeeze member which is adapted to press opening thread against the envelope when it is positioned adjacent the juncture of the flap and the body of the envelope, said gripping means being released upon completion of the thread affixing operations to enable the removal of the envelope from the said unit.

to envelopes, the combination of an envelope magazine, a rotor, an envelope carrying unit mounted on said rotor and adapted to be moved thereby into an envelope receiving position with relation to said magazine, means for withdrawing an envelope from said magazine and depositing it upon said unit, said unit including stops, means for arranging said envelope against said stops, gripping means for securing said envelope in such position, means for opening the flap of the envelope and a squeeze member for pressing the flap upon the opening thread when it is positioned adjacent the juncture of the flap and the body of the envelope so as to secure the thread to the envelope, said gripping means being released upon completion of the thread affixing operations to enable the removal of the envelope from the said unit.

53. In a machine for affixing opening threads to envelopes, the combination of an envelope magazine, a rotor, an envelope carrying unit mounted upon said rotor and adapted to be moved thereby into an envelope receiving position with relation to said magazine, means for withdrawing an envelope from said magazine and depositing it upon said unit, said unit including stops against which the envelope is arranged, gripping means for securing said envelope in such position, means for opening the flap of said envelope, a squeeze member for pressing the flap upon a section of a continuous thread to which an adhesive is applied, whereby to secure the said section to the envelope and means for severing the said section of thread from the continuous thread, said gripping means being released upon completion of the thread affixing operations to enable removal of the envelope from said unit.

54. In a machine for affixing opening threads to envelopes, the combination of an envelope magazine, a rotor, an envelope carrying unit mounted upon said rotor and adapted to be moved thereby into an envelope receiving position with relation to said magazine, means for withdrawing an envelope from said magazine and depositing it upon said unit, said unit including stops against which said envelope is arranged gripping means for securing said envelope in such position, means for opening the flap of said envelope, a squeeze member for pressing the flap upon a section of a continuous thread to which an adhesive is applied, whereby to secure the said section to said envelope, means for severing said section from the continuous thread, said gripping means being released upon completion of the thread affixing operations and means for ejecting said envelope from said unit.

55. In a machine for affixing opening threads to envelopes, the combination of an envelope magazine, a rotor, an envelope carrying unit mounted on said rotor and adapted to be moved thereby into an envelope receiving position with relation to said magazine, means for withdrawing an envelope from said magazine and depositing it upon said unit, said unit including an ejector, gripping means for securing said envelope upon the unit over said ejector, means for opening the flap of said envelope and squeeze means for pressing the flap upon the opening thread when the latter is positioned adjacent the juncture of the flap and the body of the envelope so as to secure the thread to the envelope, said gripping means being releasable upon completion of the thread affixing operations to enable discharge by said ejector of said envelope from said unit.

56. In a machine for affixing opening threads

to envelopes, the combination of an envelope magazine, a rotor, an envelope carrying unit mounted on said rotor and adapted to be carried thereby into an envelope receiving position with relation to said magazine, means for withdrawing an envelope from said magazine and depositing it upon said unit, a motor for rotating said rotor and for operating said means last mentioned, a clutch for connecting said motor to said rotor and said means last mentioned, circuit means for releasing said clutch, said unit including gripping means for securing said envelope upon the unit and a movable member for opening the flap of said envelope, said member being operative to energize said circuit means in the event that an envelope is not deposited upon said unit at the proper time.

57. In a machine for affixing opening threads to envelopes, the combination of an envelope magazine, a rotor, an envelope carrying unit mounted on said rotor and adapted to be carried thereby into an envelope receiving position with relation to said magazine, means for withdrawing an envelope from said magazine and depositing it upon said unit, a drive shaft for 100 rotating said rotor and operating said means last mentioned, a motor for driving said drive shaft, a clutch for connecting said motor to said drive shaft, circuit means for releasing said clutch, braking means for stopping said drive shaft, said unit including gripping means for securing said envelope upon the unit and a movable member for opening the flap of said envelope to facilitate positioning of the opening thread adjacent the juncture of the flap and the body of the envelope, 110 said member being operative to effect the energization of said circuit means and the operation of said braking means in the event that an envelope is not deposited upon said unit at the proper time.

58. In a machine for affixing opening threads to envelopes, the combination of an envelope magazine, a rotor, an envelope carrying unit mounted on said rotor and adapted to be carried thereby into an envelope receiving position with 120 relation to said rotor, said unit being formed with a depression, means for withdrawing an envelope from said magazine and depositing it upon said unit over said depression, a motor for operating said rotor and said means last mentioned, a 125 clutch by which said motor is connected to said rotor and said means last mentioned, circuit means for releasing said clutch, said unit including gripping means for securing the envelope upon the unit, a movable member for opening the 130 flap of said envelope to facilitate positioning of the opening thread adjacent the juncture of the flap and the body of the envelope, said member being adapted to move into said depression in the event that an envelope is not deposited upon the 135 unit at the proper time and an arm carried by said movable member, said arm being movable to energize said circuit means when said member enters said depression.

59. In a machine for affixing opening threads 140 to envelopes, the combination of a rotor which is adapted to provide a plurality of envelope receiving stations, an envelope magazine, means for rotating said rotor step-by-step to move said stations successively to an envelope receiving 145 position with relation to said magazine, means for withdrawing envelopes from said magazine and depositing them upon said rotor as said stations are moved to such position, means at each station for securing an envelope to said rotor, 150

means for applying adhesive to a thread at a substantially uniform rate, means for positioning a section of said thread adjacent the juncture of the flap and the body of an envelope, 5 means for pressing said section of thread against said envelope, whereby to secure it to the envelope, said envelope being adapted during the next advancing movement of said rotor to feed a succeeding section of said thread adjacent the

juncture of the flap and the body of succeeding envelope and means for taking up the slack in the thread between said adhesive applying means and said rotor during pauses in the movement of said rotor, said means being operative to release 80 the slack during the advancing movements of said rotor.
